Howard M. Wilson, 4138 Wade St., Los Angeles, Calif.

Filed Apr. 21, 1964, Ser. No. 79,633

Term of patent 3½ years

(Cl. D71—1)

Fig. 1

Fig. 2

Fig. 4

FIG. 1 is a side elevational view of a houseboat embodying my new design;

FIG. 2 is a plan view;

FIG. 3 is an elevational view of the right end of the houseboat of FIG. 1;

FIG. 4 is an elevational view of the left end of the houseboat of FIG. 1; and

FIG. 5 is a perspective view.

The side opposite that shown in FIG. 1 is substantially the same in appearance as the side shown.

The dominant features of my design reside in the portions shown in full lines.

I claim:

The ornamental design for a houseboat, substantially as shown and described.
